US00D844774S

(12) **United States Design Patent** (10) **Patent No.:** **US D844,774 S**
(45) **Date of Patent:** **** Apr. 2, 2019**

(54) **CATHETER ASSEMBLY DESIGN**

(71) Applicant: **Smiths Medical ASD, Inc.**, Plymouth, MN (US)

(72) Inventors: **Gursel Akcay**, Madison, CT (US); **Harsh D. Chheda**, Cheshire, CT (US)

(73) Assignee: **Smiths Medical ASD, Inc.**, Plymouth, MN (US)

(**) Term: **15 Years**

(21) Appl. No.: **29/581,199**

(22) Filed: **Oct. 17, 2016**

Related U.S. Application Data

(63) Continuation of application No. 15/012,013, filed on Feb. 1, 2016.

(51) **LOC (11) Cl.** **24-02**

(52) **U.S. Cl.**

USPC **D24/112**

(57) **CLAIM**

We claim the ornamental design for a catheter assembly design, substantially as shown and described.

DESCRIPTION

FIG. 1 is a top perspective view depicting a catheter assembly design in accordance with a first embodiment of the patent design.

FIG. 2 is a bottom view thereof.

FIG. 3 is a top view thereof.

FIG. 4 is a right side view thereof.

FIG. 5 is a left side view thereof.

FIG. 6 is a front view thereof; and,

FIG. 7 is a rear view thereof.

1 Claim, 4 Drawing Sheets
